UNITED STATES PATENT OFFICE.

CHARLES D. KUBACH, OF BALTIMORE, MARYLAND.

CONSTRUCTION OF RAILWAY TIES OR SLEEPERS.

SPECIFICATION forming part of Letters Patent No. 445,063, dated January 20, 1891.

Application filed September 11, 1890. Serial No. 364,682. (No model.)

To all whom it may concern:

Be it known that I, CHARLES D. KUBACH, a citizen of the United States, residing at Baltimore, State of Maryland, have invented new and useful Improvements in the Construction of Railway Ties or Sleepers, of which the following is a specification.

My invention relates to certain novel improvements in the construction of cross-ties or sleepers for railways, the purpose thereof being to provide a sleeper formed or molded from cement, concrete, artificial stone, or asphalt, or from a mixture of two or more of said materials, or from any suitable plastic material which when hardened possesses the requisite strength.

It is my purpose, also, to provide a railway-sleeper formed in two parts, which are mounted centrally to form a complete tie, which is strengthened in the direction of longitudinal strain by iron rods or bars placed in the mold before the plastic material is introduced, whereby said rods or bars are firmly embedded in said material.

It is my purpose, also, to provide means whereby the sleeper may be strengthened to resist crushing strains, and may be less liable to break from sudden jars or concussions.

It is my further purpose to protect the sides and corners of the ties or sleepers by an iron band which encircles said ties.

To these ends my invention consists in the several novel features of construction and new combination of parts hereinafter fully set forth, and then specifically pointed out in the claims which follow this specification.

To enable others skilled in the art to understand and use my said invention, I will proceed to describe the same in detail, reference being had to the drawings which accompany this application, and wherein—

Figure 1 is a perspective view of a sleeper or tie embodying my invention. Fig. 2 is a vertical longitudinal section of the sleeper. Fig. 3 is a detail transverse section of the sleeper. Fig. 4 is a detail view of the strengthening bars or rods shown in Fig. 1. Fig. 5 is a detail view of the connecting-pin. Fig. 6 is a detail view of the band-iron for protecting the sides and edges of the ties.

In the said drawings, the reference-numeral

1 designates the tie or sleeper, which is formed of any suitable plastic material in two parts, the division-line being substantially central. The sleeper is formed of cement and sand, 55 from furnace-slag, or from any plastic non-metallic material which may be molded into the required form.

I construct the sleeper preferably in two parts, the division-line being in the center, 60 and I connect these parts by means described as follows:

Designating the sleeper by the numerals 1 and 2, which denote the two parts thereof, I form said parts of substantially the same 65 shape, dividing them at a central point, which is provided with a resilient material 3, composed of wood veneer or any other similar and suitable material. Cast within the body of the material are connecting-pins 4, and hooked 70 over the ends of these pins are connecting-links 5 and 6. In the expanded end of the sleeper is inserted a block 7, of resilient material, preferably composed of wood veneer, having the grain arranged at different angles. 75 The rails 8 rest upon these blocks, and are fastened in place by means of plates 9, having portions 10, which rest upon the foot of the rail. Through these parts pass bolts 12, having conical ends inserted in seats in the 80 sleeper and projecting above the same, as shown in Fig. 1, to pass up through the plates 9 and receive nuts 13, by which the rail is held in place. To strengthen the half-tie, bars or rods 14 may be cast or molded therein, 85 having their ends hooked over the pins 4.

In the manufacture of this tie I form a mold the internal shape whereof substantially corresponds to the external shape of one-half of the tie. This mold is provided 90 with slots at the middle end to permit the connecting-pin to be placed in the mold with the knobs projecting through the sides of the mold. At the base end of the tie is placed a removable block or core, the exact shape of 95 the recess to be formed in the tie. It is secured in place by dowel-pins, and alongside the block is placed cores having the size and shape of the taper bolts which secure the rail. The mold is then coated inside with a 100 preparation to prevent adhesion, and the rods or bars, bent to the required shape, are

placed in the mold, the connecting-pin is placed in the bottom of the slots, the hooked ends of the rods are secured to the connecting-pins by wire, the bolt-cores are placed in their position, the slot-gate is shut down, and the cast is made, the mixture of cement, concrete, or other plastic material being filled into the mold, and any suitable degree of pressure being employed.

10. By my invention I avoid the necessity of skilled labor, since whereversand, gravel, and limestone may be had no particular skill is required in producing the sleeper, while the rail-bases of the sleepers can be made as broad as may be required, and being in two parts they are easily handled. By this construction, also, a broad base of support for the rail may be given with a less number of ties for the same space, the supporting ends of 15 the sleepers being so far widened as compared with the body portions, and being expanded to any required width.

20. To avoid the danger of repeated chipping and cracking of the exposed edge of the 25 sleeper under and in the vicinity of the rail, I apply a strengthening and protecting plate 15, which overlies the edge or angle of the expanded end of the sleeper, its ends 16 being hooked and buried in the plastic material 30 of which the sleeper is composed, as shown in Fig. 1.

What I claim is—

1. A railway-sleeper cast in two substantially equal parts meeting in the central line 35 of the track and connected by link-plates hooking over the projecting ends of pins cast in the inner ends of the divided parts of the sleeper, substantially as described.

2. A railway-sleeper formed of plastic material cast or molded in two substantially equal parts, each having a transverse pin cast 40 in or near its inner end and provided with tie-rods buried in the plastic material and hooking at one end over said transverse pins, 45 and link-plates hooked over the projecting headed ends of said transverse pins, substantially as described.

3. A railway-sleeper composed of plastic

material suitably molded and formed in two parts, united centrally, or substantially so, 50 each part having a broadened end containing a resilient base or support for the rail, whereby an increased or extended base of support is provided with a less number of sleepers, substantially as described.

4. A railway-sleeper formed of cement or other plastic material in two substantially equal portions, each having a transverse pin cast therein and being provided with tie-rods cast longitudinally in each half part and having their ends hooking over said transverse pins, and link-plates hooking over the projecting headed ends of the transverse pins, each molded half part of the sleeper being provided with a resilient base or support for 60 the rail, substantially as described.

5. A railway sleeper or tie composed of two substantially similar parts, each molded of plastic material and united by suitable connections, the supporting end of each sleeper 70 having a resilient base of support inserted therein and extended in a direction transverse to the tie, and being provided also with strengthening-bars cast in the material forming the sleeper, substantially as described.

6. In a railway-sleeper formed of plastic material and having inserted in the ends resilient material to form a support for the rails, the combination, with bolts having flaring heads engaging with corresponding recesses 80 in the sleeper, of clamping-plates engaging the foot of the rail and the ends of the bolts, substantially as described.

7. A railway-sleeper formed of plastic material cast or molded in two substantially 85 similar parts connected by tie-plates, a resilient material being interposed between the abutting ends of said parts, substantially as described.

In testimony whereof I have affixed my signature in presence of two witnesses.

CHARLES D. KUBACH.
